CIGAR OR CIGARETTE EXTINGUISHER

Manuel de la Torre, Houston, Tex.

Application July 12, 1946, Serial No. 683,028

2 Claims. (Cl. 131—256)

1

This invention relates to a cigar or cigarette extinguisher.

An object of the invention is to provide novel means specially designed to receive a plurality of lighted cigar or cigarette stubs to extinguish the stubs and thereafter eject the extinguished stubs from the extinguisher.

Another object of the invention is to provide a cigar, or cigarette, extinguisher which will readily receive lighted stubs and quickly extinguish them.

It is a further object of the invention to provide an extinguisher of the character described that may be easily cleansed without affecting the working parts or the functioning of the device.

Novel means have also been provided which will prevent the clogging of the stub receivers by the stubs and the ashes as the stubs are successively delivered thereto and ejected therefrom.

The extinguisher also includes novel means for holding a partly used lighted cigar or cigarette.

It is still a further object of the invention to provide an extinguisher of the character described which is very compact, is of neat appearance, which may be cheaply and easily produced and which has few parts not liable to wear or get out of order by constant use.

With the above and other objects in view the invention has particular relation to certain novel features of construction, operation and arrangement of parts, examples of which are given in this specification and illustrated in the accompanying drawings, wherein:

Figure 1 is a vertical, sectional view of the extinguisher showing the parts in stub discharging position taken on the line 1—1 of Figure 2.

Figure 2 is a transverse sectional view taken on the line 2—2 of Figure 1.

Figure 3 is a plan view of the ejector.

Figure 4 is a vertical sectional view of another embodiment showing only a two bore receiver and showing the parts in stub receiving position.

Figure 5 is a cross sectional view on the line 5—5 of Figure 4; and

Figure 6 is a vertical sectional view thereof taken on the line 6—6 of Figure 4.

Referring now more particularly to the drawings wherein like numerals of reference designate the same parts in each of the figures, the numeral 1 designates the receiver which may be of any selected design and which has, in the preferred form, a plurality of bores 2 therein whose upper ends are preferably flared and whose

2

lower ends 2a are reduced in diameter. The upper ends of the bores are flared so as to facilitate the insertion of the lighted stubs to be extinguished into said bores. The portion of each bore between the flared upper end and the reduced low end is of approximately the same diameter as that of an ordinary cigar, or cigarette, so that when the stub is inserted therein the bore will be substantially closed to exclude any appreciable amount of air from the lighted end of the stub. The lower end of each bore is gradually reduced as shown so as to conform to the shape of said lighted cigar, and to conduct to a quicker extinguishing of the fire and said lower end terminates in an approximately cylindrical outlet.

The receiver 1 is formed with a plurality of bores 2. As shown in Figures 1 and 2 there are three bores 2 but as shown in Figures 4 to 6, 20 inclusive, there are only two of said bores shown.

As shown in Figures 1 and 2 the receiver is secured to the lower end of a tubular stem 3 which extends on down through the receiver, as shown. Within the upper end of the stem there is a coil spring 4 whose upper end contacts the plug 5 which closes the upper end of the stem and whose lower end is seated against the upper end of the guide 7. This guide is fastened to the bottom of an ash tray 8 by means of a clamp nut 9 which is threaded onto the lower end of said guide and the guide projects up into the lower end of the stem and its upper end is flared forming a head 10 adapted to engage an inside annular shoulder 11 to prevent detachment of the stem from the guide.

It will be noted that the central portion of the bottom of the ash tray has an elevated platform 12 to the center of which the guide 7 is secured. The upward movement of the stem 3 is limited by the engagement of the shoulder 11 with the head 10 and the downward movement is limited by the platform 12.

There is an ejector formed with a flat base 13 and with upstanding arms 14 whose upper ends are formed with the outwardly turned flat fingers 15.

Each bore 2 is formed with an inside radially extended slot 16 which extends from the lower to the upper end thereof and into which the upper ends of the arms 14 project.

It will be noted from an inspection of Figures 1 and 2 that the fingers 15 fall short of the vertical axis of the corresponding bore 2.

The base 13 has a central opening 17 and this base is located directly on the platform 12 and

the lower end of the guide 7 extends through said base so that the ejector will be clamped in place by the clamp nut 9.

The spring 4 will normally hold the receiver elevated with the ejector arms in the lower ends of the corresponding slots 16.

In operation the user may insert as many lighted stubs as there are vacant bores in the receiver leaving the inserted stub, or stubs, in position until extinguished. On account of the exclusion of air and on account of the close contact of the lighted end of the stub with the reduced lower end of the bore the lighted stub so inserted will be quickly extinguished without applying any pressure on the stub whatsoever. When all the bores are filled with the stubs the stem 3 may be moved downwardly thus forcing the receiver 1 downwardly until it engages the platform 12. During this downward movement the arms 15 will prevent downward movement of the stubs in the bores so that when the receiver has been moved to its lowermost position the stubs will be unsupported and will discharge by gravity outwardly and downwardly into the ash tray 8 and upon relief of the pressure the spring 4 will return the empty receiver to its upper position ready to receive another series of lighted stubs.

In the embodiment illustrated in Figures 4, 5 and 6 the receiver is shown as having only two bores 2. In this embodiment of the invention there is an upstanding bracket 18 whose lower end is overturned and rests on the platform 12 and the lower end of the stem 3a is reduced and externally threaded and extends through said overturned end and through said platform and the clamp nut 9 is threaded onto said lower end to secure said parts assembled.

In this form of the invention the receiver 1a is secured onto the lower end of the tubular stem 3a, said lower end being provided with an outwardly turned flange 6 to retain the receiver thereon and the upper end of the bracket 18 is provided with an overturned stop 19 against which the receiver engages to limit the upward movement of the receiver.

In this form of the invention each bore 2 is provided with a slot 16a, said slots 16a extending approximately radially with respect to the bores 2.

The bracket 18 has the overturned fingers 20, 21 which extend into said slots 16a.

Within the stem 3a there is a compression spring 4 whose upper end bears against the plug 5 and whose lower end bears against the upper end of the guide 7a.

The spring 4 will normally hold the receiver 1a in elevated position with the fingers 20 at the lower ends of the slots 16a.

Upon insertion of a lighted cigar, or cigarette, stub into a bore 2 it will be extinguished, as hereinabove explained, and when the bores are filled the stem may be depressed placing the spring 4 under compression and moving the receiver 1a downwardly relative to the fingers 20 thus correspondingly elevating the stubs relative to the receiver, said stubs being supported by the fingers 20 and on account of said fingers being located inwardly of said central lines of the bores the

ejected stubs will be overbalanced and fall outwardly.

Upon relief of the pressure the spring 4 will again elevate the receiver. It may be here stated that the fingers 15 and 20 will also operate to clean the lower ends of the bores of any ash or other clogging material that may accumulate therein.

It may be also stated herein that the fingers 15 fall short of the centers of their corresponding bores 2, as hereinabove stated, so that the ejected stubs will be overbalanced and will fall outwardly of the respective bores.

As is clearly illustrated in Figures 4 and 5 the bracket 18 is laterally extended and formed with the upwardly curved wings 21, 21 whose upper ends are provided with notches 22, 22 to receive partially used cigars, or cigarettes, which may be inserted and temporarily held therein.

The tray 8 may be of any selected design provided with an upstanding marginal rim to retain the contents thereof.

The drawings and description are illustrative merely while the broad principle of the invention will be defined by the appended claims.

What I claim is:

1. A stub extinguisher comprising, a receiver having a stub receiving bore, the lower end of the bore being tapered, said receiver having a slot 30 extending from the upper to the lower end thereof through the wall of the receiver and to the bore, and an ejector one end of which is arranged to work in said slot and is formed with an extension which projects into the bore, said extension being offset relative to the axis of the stub receiving bore, and said receiver being movable relative to the ejector to eject said stub from the bore.

2. A cigar or cigarette extinguisher comprising, a platform, a guide upstanding therefrom, a stem slidable on the guide, a receiver fixed to the lower end of the stem and having a bore therethrough shaped to receive a stub and provided with a vertical slot extending radially from said bore, an ejector fixed on the platform and arranged to work in said slot and which projects into said bore, yieldable means normally maintaining the ejector at the lower end of the slot and means permitting relative movement of the receiver and the ejector to displace the stub from said bore.
